CREAM SEPARATOR

Howard Albert Kisner, Fairmont, W. Va.

Application March 25, 1939, Serial No. 264,217

1 Claim. (Cl. 210—51.5)

This invention appertains to new and useful improvements in cream separators especially adapted for milk bottle use.

The principal object of the present invention is to provide a cream separator which can be easily handled and which will not require tilting of the bottle in separating the cream from the milk.

Other objects and advantages of the invention will become apparent to the reader of the following specification.

In the drawing:

Figure 1 represents a side elevational view.

Figure 2 is a fragmentary sectional view on the line 2—2 of Figure 1.

Figure 3 is a fragmentary perspective view of the upper portion of the separator.

Referring to the drawing wherein like numerals designate like parts, it can be seen that numeral 5 represents the cylindrical container wall which has a downwardly converging bottom 6 of frustoconical shape, the extreme lower portion of which is open as at 7 and this forms a seat for the conical-shaped valve 8, upwardly from which extends the stem 9. This stem 9 is threadedly engaged as at 10 into the valve element 8 and extends upwardly through the uppermost portion 11 of the frame generally referred to by numeral 12, the same terminating at its upper end in the hand grip 13 between which in the portion 11 of the frame is the coiled compressible spring 14, serving to normally maintain the valve 8 seated.

The frame 12 is of one piece construction, the same having the depending diverged leg members 15—15 riveted or otherwise secured at their lower ends to the container 5 as at 16. The upper portions of the legs 15 flare outwardly as at 17 and then extend back inwardly to merge with the

frame piece 11. Thus the portions 17 define finger holds which can be used in conjunction with the handle 13 in manipulating the valve 8 and lifting the container from a milk bottle, the bottle being denoted by numeral 18.

While the foregoing specification sets forth the invention in specific terms, it is to be understood that numerous changes in the shape, size and materials may be resorted to without departing from the spirit and scope of the invention as claimed hereinafter.

Having described the invention, what is claimed as new is:

A cream separator comprising a tubular container for insertion endwise into a bottle in upright position and having a tapering lower end forming a reduced aperture therein, a frustoconical valve member movable upwardly and downwardly in said aperture to close and open the same, respectively, an operating rod extending from said member upwardly out of the container and having a thumb-piece on the upper end thereof for pressing the same downwardly to correspondingly move said member, a single piece strap metal frame extending upwardly from the container and comprising a pair of straight side stretches converging from opposite sides of the container into engagement with opposite sides of said rod to form therebetween a lower guide for said rod, an upper cross stretch through which said rod is slidably extended and forming an upper guide for the rod, and a pair of upwardly arched stretches connecting said side stretches to said cross stretch upon opposite sides of the rod and forming finger grips for suspending said frame from the fingers, and spring means tensioning said rod against downward movement.

HOWARD ALBERT KISNER.
